[57] CLAIM

The ornamental design for a low-voltage track lighting fixture, as shown.

DESCRIPTION

FIG. 1 is a front perspective view of the design of this application;

FIG. 2 is a rear perspective view of the design of this application;

FIG. 3 is a top plan view of the design of this application;

FIG. 4 is a front elevation of the design of this application;

FIG. 5 is a bottom plan view of the design of this application;

FIG. 6 is a right side elevation of the design of this application;

FIG. 7 is a left side elevation of the design of this application; and,

FIG. 8 is a rear elevation of the design of this invention.
